METHOD AND APPARATUS FOR COOLING MILL ROLLS

Application filed April 6, 1932. Serial No. 287,965.

The present invention relates to the preparation of rubber, particularly to the milling of rubber, and to an improved mill roll cooling apparatus by which the efficiency of 5 the devices used for chilling the rolls is increased and superior results are obtained.

In present systems it is the custom to spray the interior of the mill roll by numerous jets of water which strike against the upper side 10 of the interior of the roll, the water collecting in a pool in the bottom of the roll from which it is siphoned or drained off. No attempt has been made, prior to the present invention, to change the body of air within the 15 roll, which, so far as known to me, has always been static, and as a result the entire cooling effect is produced by the difference in temperature of the water entering the roll. The cooling of the mill rolls of a modern rubber plant requires a large volume of water and the efficiency of the cooling apparatus is governed by the temperature of the water 20 and its quantity. Inadequacies of water supply and the inability to maintain it at a low temperature, particularly during the summer months, unfavorably affect the operation of the factory and increase the expenses of operating the mill room.

It is the purpose of the present invention to devise and perfect an improved method and apparatus for cooling mill rolls whereby lower temperatures in the rolls may be obtained with less water or with water at a higher temperature and the efficiency of the mills may thereby be increased.

Briefly stated, the object of the invention is effected by increasing the rate of evaporation of the water on the interior of the mill roll and this may be done by several methods, 40 two of which are illustrated and described herein.

In the drawing, the showing is restricted to such parts of the apparatus as require illustration, the mill roll housings and driving mechanism being omitted as any well known form of mill may be constructed with the improvements herein described.

Figure 1 is a sectional view of a mill roll equipped with one form of the invention, this 45 particular embodiment of the invention uti-

lizing the vacuum system to be described; and

Figure 2 is a similar view illustrating the pressure system.

Referring particularly to Figure 1, a mill 55 roll of an ordinary rubber working mill is illustrated at 1, the bearings being indicated at 2. Located at the axis of the mill roll is the horizontal spray pipe 3, which extends the length of the interior of the roll and is 60 provided with a plurality of apertures from which the water issues in a fine spray against the interior of the roll. In the ordinary operation of a device of this character, the water is allowed to collect in a pool at the bottom 65 of the roll from which it is drained or siphoned off. In this operation, the sole cooling effect is produced by the spraying of the interior of the roll with a large volume of 70 water, the efficiency of the apparatus being controlled solely by the temperature of the water and its volume.

The invention herein contained, however, consists in promoting the evaporation of the 75 water and this is done in the form of the invention here under discussion by subjecting the interior of the roll to a vacuum, which may be exerted through the pipe 5. The vacuum which is applied to the interior of the 80 roll promotes and increases the rate of evaporation of the water in the interior of the roll by reason of the well known physical law that evaporation varies inversely as the barometric pressure. It will be appreciated 85 that in the usual operation, the interior of the roll is filled with a heavy mist due to such evaporation as takes place by the contact 90 of the water with the hot roll. In the method described, however, the mist or vapor is positively withdrawn and consequently the water in the spray will evaporate much faster than under ordinary conditions. The temperature at which the water evaporates is lowered by reason of the sub-atmospheric 95 pressure in the roll and consequently the efficiency of the cooling system is greatly increased.

As an alternative for the vacuum system, that shown in Figure 2 may be substituted, 100 in which the roll is indicated at 10 and the

- spray pipe at 11. In this drawing, the water in the interior of the roll is allowed to overflow at one end 12. The opposite end of the mill roll is connected to a source of air 5 under pressure, indicated at 14, the air being circulated through the roll in a large volume so that the water will evaporate more rapidly than with a static condition of the air in the interior of the roll.
- 10 The invention shown and described herein may be embodied in other forms than those specifically illustrated and the invention may have a wider scope than that described within the scope of the appended claims.
- 15 What is claimed is:
1. An apparatus for cooling rolls for the uses and purposes set forth, comprising a hollow roll, a pipe extending in the roll and having means for spraying the interior of 20 the roll, and means for effecting circulation of air through the roll thereby increasing the rate of evaporation of the water in the interior of the roll above the rate of evaporation obtainable with a static body of air in the 25 roll.
  2. The method of cooling mill rolls comprising spraying the interior of the roll with water and increasing the rate of evaporation of the water in the interior of the roll over 30 the rate of evaporation obtainable in a static body of air in the interior of the roll by producing a rapid circulation of air through the interior of the roll.
  3. The method of cooling mill rolls comprising spraying the interior of the roll with water in finely divided state whereby the interior of the roll is filled with vapor, and circulating air through the interior of the roll whereby the rate of evaporation of the water 35 is increased over that obtainable with a static condition of the air within the roll.
  4. The method of cooling mill rolls comprising spraying the interior of the roll with water in a finely divided state, increasing the 40 rate of evaporation of the water in the spray over that obtainable with a static body of air, by producing a constant replacement of the water saturated air in the interior of the roll by unsaturated air, thereby reducing the temperature of the spray.
  5. The method of cooling mill rolls comprising subjecting the interior of the roll to a water spray and reducing the temperature of the water in the spray by increasing its rate 45 of evaporation over that obtainable in a static body of air within the roll by the movement of air through the spray.
